UNITED STATES PATENT OFFICE.

ALFRED HEALD, OF PHILADELPHIA, PA., ASSIGNOR TO HUGH McCALLUM, ORLANDO CREASE, AND ANDREW J. SLOAN, ALL OF SAME PLACE.

DESIGN FOR A CARPET.

SPECIFICATION forming part of Design No. 13,583, dated February 6, 1883.

Application filed December 26, 1882. Term of patent 3½ years.

To all whom it may concern:

Be it known that I, ALFRED HEALD, a citizen of the United States, and a resident of Philadelphia, Pennsylvania, have invented or produced a new and original Design for a Carpet-Pattern, of which the following is a specification.

My design is fully shown in the accompanying photographic illustration.

10 The design comprises a stem, with leaves and flowers arranged on a background having fine sprays of foliage, as fully shown in the illustration.

Irrespective of the colors employed, I claim—
The design for a carpet-pattern, substantially as described and shown.

In testimony whereof I have signed my name to this specification in the presence of two subscribing witnesses.

ALFRED HEALD.
